United States Patent Office.

ADAM ERNST, OF MILWAUKEE, WISCONSIN.

Letters Patent No. 65,554, dated June 11, 1867.

STOVE-PIPE DRUMS.

The Schedule referred to in these Letters Patent and making part of the same.

TO WHOM IT MAY CONCERN:

Be it known that I, ADAM ERNST, of Milwaukee, in the county of Milwaukee, and State of Wisconsin, have invented certain new and useful improvements in Heating Apparatus; and I hereby declare the following to be a full, clear, and exact description of the same, reference being had to the accompanying drawings, in which—

Figure 1 is a vertical central section of an apparatus constructed in accordance with my invention; and

Figure 2 is a like section of a modification of the same.

Figures 4 and 5 are transverse sections of the apparatus, shown in figs. 1 and 2 respectively.

The object of my invention is to utilize the heated product of combustion which in ordinary stoves is drawn off directly through a chimney flue into the outside air. A great amount of heat is thus wasted which might be applied to heating other rooms or apartments, or to more thoroughly heating the apartment in which the furnace or stove is located.

My invention consists in a heating apparatus in which flues are formed for the passage of the products of combustion and air to be heated in the manner hereinafter described, and which is capable of being readily applied to or used in connection with stoves or furnaces of ordinary construction.

This apparatus may be either attached to the stove itself or placed at any point on the smoke pipe or flue, so that if the stove be in one room the pipe may extend through the wall into the next adjoining room, or through the ceiling into the room above, where the heating apparatus can be connected or joined to the pipe so as to utilize all the heat passing up through it, and to thoroughly warm the room.

The apparatus consists of a drum or casing enclosing an outer helical or spiral flue, through which the smoke and heat pass from the stove when desired. This annular flue encloses another flue (the two being entirely separate and having no communication with each other) which communicates with the outside air. There may be also a third flue, if it be desired, either enclosed within the air flue or placed on one side of the apparatus, which is provided with a damper or valve, and like the outer helical flue is intended to receive the products of combustion.

When the apparatus is to be used for heating purposes the damper is turned so as to close this flue, which directs the products of combustion up through the outer winding passage, heating the air in the inner flue and at the same time causing the heat to radiate from the exterior of the drum.

When no more heat is required, or it is desired to direct the heat to another room still further on, the damper or valve above mentioned is opened, and the smoke and heat pass up through the straight or tubular flue, and are carried off to the point where they are to be used.

In the drawings, I have represented two modifications of my invention. The apparatus shown in fig. 1 is intended to be applied to the top of an ordinary stove, or it may simply have a fire-pot or chamber formed under it. It consists of an outer drum or casing, A, in which is formed a spiral or helical flue, a, enclosing the air flue b. The two flues have no communication with each other. The air flue is closed at the bottom, and the air flue b. The two flues have no communication with each other. The air flue is closed at the bottom, and communicates with the exterior air by means of a tube, b', which passes through the helical flue a and drum A; the flue a is of course open at the bottom to receive the heat, &c., from the fire, and at its upper end opens into the side flue c, which is put in communication with the lower part of the annular chamber surrounding the air flue b by means of the branch pipe c'. A damper, d, is placed in the side flue, by means of which the products of combustion may be either drawn off directly through this flue or directed into the helical flue or radiator a.

The operation of the apparatus is as follows: When the damper d is closed, the heated products of combustion, passing up through the open bottom of the chamber A, will be carried through the spiral or helical flue a. In their course through this annular and spiral chamber they will not only cause the heat to radiate from the exterior drum A, but will heat the air within the inner drum or flue b, which air becoming rarefied ascends, its place being supplied by the cold air drawn in through the pipe b'. After passing up through the helical flue, the products of combustion pass out into the pipe c. The heated air in the flue b is discharged from the open mouth of the flue, or is conducted off to any desired point by means of additional length of pipe fitted over the top of the flue. If it be now desired to put a stop to the heating of the air, the damper d is

opened, in which case the products of combustion will of course be drawn off in great part, if not altogether, through the shorter and more direct flue or passage *c*. By this means they are kept from contact with the inner flue *b* and helical drum *a*, and can be conducted off rapidly and without any considerable loss of heat to other rooms requiring to be heated. In such case apparatus may be employed similar to that shown in fig. 2, in which the upper and lower ends *e* of the drum or casing *A* are contracted so as to fit the pipe to which they are applied. The relative positions and general arrangement of the spiral flue *a* and air flue *b* are unchanged, but instead of placing the side flue *c* on the exterior of the drum *A* it is placed within the air flue, by which arrangement the apparatus is divided up into three concentric chambers. The flue *c*, as in fig. 1, is provided with a damper, *d*, by operating which, as before explained, the products of combustion are either drawn up directly through the centre flue or directed into the helical flue or radiator. In order to admit of the free discharge of the heated air the casing *A* is divided into two sections, the internal arrangement of which is the same, connected by tubes or pipes *f* opening into the helical passage or flue in the upper and lower sections. The inner or direct smoke flue *c* extends uninterruptedly from one end of the apparatus to the other. Under this arrangement the annular air-chamber *b* is entirely open at the top, so that the air drawn in through the tube or throat *b* when heated is free to escape from the annular openings *b*² at the top.

It will be seen that in this modification the inner flue *c* is in reality the ordinary smoke flue or pipe, surrounded as described by an annular air-chamber and helical flue. By connecting the helical flues by pipes *f*, as represented, the heated products of combustion are not only enabled to pass with facility from the lower section to the upper, but the exterior heating surface is considerably increased in area.

It will be seen that the two forms of apparatus, shown in illustration of my invention, are essentially the same in principle. They are each provided with a flue for carrying off the products of combustion with as great rapidity and as little loss of caloric as possible; and they have a helical passage through which the products of combustion pass more slowly, so as to give out or radiate a greater amount of heat. These two flues are connected in such manner that the heat may be directed either wholly or partially through the one or the other according as a greater or less degree of heat is required, and they are arranged and combined in a radiator or drum formed so as to admit of their ready application to any fire-pot, or stove, or pipe of ordinary construction.

Having described my invention and the manner in which the same is or may be carried into effect, what I claim, and desire to secure by Letters Patent, is—

1. The herein-described heating apparatus, the same consisting of a drum or radiator capable of being applied to a stove or pipe of ordinary construction, and provided with flues arranged substantially in the manner and for the purposes herein shown and specified.
2. The combination and arrangement of the inner or direct smoke flue, and annular air-chamber surrounding the same, with the outer helical flue or radiator, and the pipes or tubes for connecting the sections into which the said flue is divided, substantially as herein described.

In testimony whereof I have signed my name to this specification before two subscribing witnesses.

ADAM ERNST.
